CANOPY FRAME MOUNTING FOR CHAIRS

Robert D. Vanderminden, Granville, N. Y., assignor to The Telescope Folding Furniture Co., Inc., Granville, N. Y., a corporation of New York

Application June 10, 1952, Serial No. 292,678

2 Claims. (Cl. 135—7.1)

1

This invention relates to a canopy frame mounting for chairs, more particularly folding chairs of the lawn or beach type.

In chairs of this type canopies of various types have heretofore been in use which are adjustably secured to the back uprights by means of bolts and wing nuts designed to be tightened on the bolts to secure the canopies in adjusted positions. One of the difficulties frequently encountered with these arrangements is the loosening of the nuts on their bolts as a result of adjustment of the canopies or of closing of the chairs to folded condition and often the annoying loss of such nuts. This loosening occurs because of the motion of the canopy supporting straps on their bolts relative to the securing nuts with consequent loosening rotation thereof each time the canopy is swung for adjustment or to a folded position.

Principal objects and features of the present invention are the provision of novel canopy mounting means which eliminates entirely any tendency for loosening of the nuts on their bolts irrespective of the frequency or extent of pivotal adjustment or folding of the canopy relative to the body of the chair.

Further objects and features of the invention are the provision of novel canopy mounting means that is simple and effective mechanically and which may be utilized without modification on existing chairs.

Further objects and features of the invention will become apparent from the following specification and accompanying drawings wherein:

Fig. 1 is a perspective view of a canopy frame mounted in position of use to a chair of the type described, only a portion of the chair being shown;

Fig. 2 is a fragmentary sectional view taken along line II—II of Fig. 1; and

Fig. 3 is a sectional view taken along line III—III of Fig. 2.

The chair itself (only partially shown) includes the usual rear uprights 10 and 11 joined by a cross bar 12 which serves as a support for the back 13 of canvas, duck or other suitable material.

The canopy frame comprises side bars 14 and 14a joined at their front ends, for example, by a front wire spreader 15 pivotally engaging each of the side bars and covered by canopy material 16 similar to that of the back 13.

The canopy frame mounting means by which the frame is adjustably secured to the uprights 10 and 11 of the chair include a pair of straps 17 and 18 pivotally secured at spaced apart points 19 and 20 to opposite sides of each side bar 14 and

2

14a of the frame. The straps 17 and 18 of each pair near their ends most removed from their pivotal supports 19 and 20 have non-circular holes 21 and 22 therein, which, preferably, are square or have other polygonal shapes. The straps 17 and 18 of each pair are bent outwardly at 17a and 18a so that the spacing between the parallel portions thereof bearing holes 21 and 22 is substantially that of the thickness of the uprights 10 and 11.

The uprights 10 and 11 near their upper ends each have a transversely extending bolt hole 24, preferably of somewhat larger diameter than that of the strap holes 21 and 22. Straps 17 and 18 of each pair are positioned respectively to embrace one of the two uprights 10 and 11 and with their holes 21 and 22 aligned with the bolt holes 24 of these uprights. A headed bolt 25 having a portion 26 of non-circular cross section, corresponding in shape and substantially with the dimensions of holes 21 and 22, is then inserted through the aligned holes 21, 24 and 22 of each pair with its head 27 in surface contact with the outward face of one of the straps 17 or 18 of each pair and with its non-circular portion engaged in, for example, the hole 21 of a strap 18 of each pair. A wing nut 28 or other suitable nut is screwed onto the threaded end 29 of each bolt 25 projecting outwardly of the hole 22 in strap 17 of each pair and is tightened thereon to clamp the respective uprights 10 or 11 firmly between a pair of the straps 17 and 18.

Because of the non-circular shape of hole 21 in each strap 18 and the engagement of its edges with the correspondingly shaped portion 26 of the bolt 25 extending therethrough, the bolt 25, members 17, 18 and wing nut 28 rotate as a unit whenever the canopy is rotated for adjustment, thereby eliminating possibility of accidental loosening of each wing nut 28 on its bolt 25. In consequence, repeated pivotal adjustments of the canopy frame to desired positions may be made without loosening or tightening of said nuts, thereby eliminating possibilities of loss of nuts or bolts.

Moreover, it will be noted that the respective pairs of straps 17 and 18 lie on opposite sides of the respective uprights 10 and 11 and embrace them and that the heads 27 of the bolts and the wing nuts 28 bear respectively against the outward faces of the said straps. Thus the friction between the contacting surfaces of bolts, nut and straps has the tendency to rotate each bolt, nut and their associated straps in unison, minimizing any tendency for the nuts to loosen or tighten

on the bolts. Hence, even if the bolts are circular in cross section the canopy frame can be adjusted with minimum danger of loosening of the nuts. However, the preferable inclusion of the non-circular portions 26 on the bolts to engage in corresponding non-circular holes 21 in the straps 18 provides positive prevention of any accidental loosening or tightening of said nuts on said bolts during positional adjustments of the canopy frame.

While specific embodiments of the invention have been described and shown, variations in structural detail within the scope of the claims are possible and are contemplated. There is no intention, therefore, of limitation to the exact details described and shown.

What is claimed is:

1. A chair having back uprights provided with transverse holes and a canopy frame supported by said uprights, said frame having oppositely located side bars, and means for mounting the canopy frame adjustably from the uprights comprising a pair of straps secured pivotally at spaced-apart points to each side bar, each pair of straps having spaced-apart portions for positioning the straps of the pair to embrace an upright on its opposite sides, said straps having aligned openings in their spaced-apart portions for alignment with the transverse hole of the upright which they embrace, headed bolts, one extending through the aligned holes of each pair of straps and the transverse hole of the upright

which each pair of straps embrace with the bolt head engaging the outward face of one strap of said pair, the hole in one of each pair of said straps having a non-circular shape and the bolts having non-circular portions to fit and engage in the non-circular holes of said straps, and a clamping nut screwed onto each bolt engaging the outward face of the strap other than that engaged by the bolt head, the bolts, nuts and pairs of straps associated with them being rotatable as a unit during adjustment of the canopy frame, thereby eliminating accidental loosening of the nuts on the bolts during adjustment.

2. The chair of claim 1 wherein the straps of each pair are pivotally supported at opposite sides of the respective side bars and wherein the side bars are joined at their front ends by a wire spreader pivotally engaging each of the side bars.
